FORE PART ROUGHING MACHINE
FOR SHOES

Arthur T. Tempesta, Lewiston, Maine, assignor,
by direct and mesne assignments, to Compo
Shoe Machinery Corporation, Boston, Mass., a
corporation of Delaware

Application March 10, 1934, Serial No. 714,952

4 Claims. (Cl. 69—1)

This invention relates to upper roughing machines for use in the manufacture of cemented shoes.

Heretofore the most widely practised method of doing this work was to hold the shoe against an upstanding guard through which projected a portion of a revolving wire brush wheel, the abrading effect of the wheel causing the leather to be reduced to the proper thickness and bringing it into a condition best suited to receive the glue or cement by which the outer sole is secured to the shoe.

The difficulty experienced by the ordinary workman in operating by this method resides in the lack of a proper and positive guiding element which would prevent his lowering the shoe to such an extent that the wire brush wheel makes contact with the upper above the inturned lasting allowance, often causing serious damage to the shoe.

In my present invention I provide an element against which the edge of the shoe abuts and across which it is drawn while the wire brush wheel is acting on the overlapping part to bring it to the desired thickness and roughness.

The gauge is adapted to be raised or lowered on the guard so that various different presentations of the shoe to the brush may be obtained, and a greater or lesser amount of material abraded. It enables the workman to procure a uniformity in the roughened surface and prevents injury to the shoe which might otherwise occur.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawing, in which:

Fig. 1 shows, on a reduced scale, a simple form of roughing machine, and

Fig. 2 an end elevation thereof;

Fig. 3 is an elevation of the guard member;

Fig. 4 is an elevation of the face of one form of the gauge element;

Fig. 5 is a side elevation of the gauge shown in Fig. 4;

Fig. 6 is a section on line 6—6, Fig. 7, the view

showing portions of the gauge member and portions of the guard and a fragmentary view of the roughing wheel acting on the overlasted margin of the shoe upper;

Fig. 7 is an elevation of the guard, gauge and wheel, with a shoe shown abutting on the wheel;

Fig. 8 is a section on line 8—8, Fig. 7, showing a tapered overlapping portion after being acted on by the wheel;

Fig. 9 shows the gauge lower than in Fig. 8, making a substantially even thickness overlapping part;

Figs. 10, 11, 12, 13 and 14 show various forms of gauge elements, and

Fig. 15 shows a modification in the form of the guard.

Referring to the drawing, 1, 1, represent the supporting legs of a roughing machine having bearings 2, 2 in which is journaled the revolute shaft 3, the latter being driven by any suitable means, as by the pulley 4.

Mounted on one end of the shaft 3 is a wire brush wheel 5 encased in a hood 6 which is secured in any convenient manner to the side of one of the supporting legs.

On the front side of the hood is mounted an upstanding guard member made in the form of a plate 7, having slots 8 through which pass, respectively, the attaching bolts 9 which may be anchored to casing 6 or to a suitable standard supported directly from the machine frame. The slots 8 provide for lateral adjustment of the guard with respect to the wire brush wheel. A shoulder or flange 8a is cast with and projects rearwardly from the guard plate 7. This shoulder is adapted to seat on the lower wall of the casing, and may preferably be of less width than the casing in order to permit the lateral adjustment provided by slots 8.

An aperture 10 permits the wire brush wheel 5 to project through the guard a short distance, the latter varying according as the guard is adjusted toward or from the wheel by the attaching bolts 9.

The guard has a slide-way 11 within which is disposed a stop gauge 12. The gauge is provided with an oblong slot 13 through which the bolt 14 passes to secure the gauge to the guard. By relaxing the bolt 14 the gauge may be adjusted on the guard to any position desired to bring the shoe, abutting on the gauge, to the proper angle of presentation to the wire brush wheel.

In Fig. 4 I illustrate one of the simplest forms of my gauge element. It comprises a block

55

portion $12a$ from which depend two legs $12b$. The lower end of the block portion is tapered and the apex or gauge point $12c$ is positioned midway the two legs, but outwardly therefrom, as shown in side view in Fig. 5.

The inner side of each of these legs, at a , is brought to a comparatively thin edge, and laterally thereof each leg, preferably, is convex on its outer face.

10 These edges a contact the lasting allowance Ua of the upper U , and extend entirely across the bottom of the shoe, so that together with gauge point $12c$, they control the position and plane of the shoe bottom with respect to the roughing wheel. Thus, during the roughing operation, the upper, which is supported by the last L , may be held by the operator in full line contact against the edges a , which latter, being quite closely spaced, insure a very accurately and uniformly 15 scarified surface.

By observing Fig. 6 it will be noted that the shoe-contacting edges a of the legs extend for a considerable distance outwardly from the face of the guard 7 . This enables the workman to 20 grasp the shoe to better advantage than if they were nearer in line with the face of the guard member.

The uppers of certain types of shoes varies from others in thickness and in certain other requirements, which variance necessitates repositioning the gauge, vertically, on the guard.

In some cases the lasting allowance is scarified in such a manner that what is left is substantially V-shape, as shown in Fig. 8. In this 35 instance the gauge is set so that the wire wheel abrades the leather more deeply on the inner edge of the overlapping portion than on its outer part, causing the desired feathering of the lasting allowance.

40 In Fig. 9 the gauge is shown lowered on the guard. This brings the lasting allowance of the upper substantially on the axial line of the wire brush wheel, and an abrasion is made which leaves this part of the upper of very nearly an even thickness.

45 Thus, by raising or lowering the gauge 12 , various shapes in cross section of the overlapping portion are obtainable, the guard 7 being suitably adjusted away from the work contacting surface of the rougher at the time gauge 12 is lowered.

50 Various modifications in the form of the gauge 12 are possible. In Fig. 10 the gauge point is made rotatable by employing a roll against which the side of the shoe abuts as it is moved transversely of the legs $12b$.

Figs. 12 and 13 show for the leg structure rolls $12d$ mounted on studs $12e$. In this design 60 rotating contact of both legs and gauge point is provided.

65 In Fig. 14 a somewhat more pronounced departure from the structure shown in Fig. 7, with respect to the leg design, is illustrated. In this instance the shoe-contacting surfaces of the legs is inclined with respect to the face of the guard 7 . The particular purpose to which this design might be put is when it is desired to scarify the lasting allowance very close to the side of the shoe, or where the inturned lasting allowance joins the sides of the upper.

70 Fig. 11 shows the gauge as a flat, straight surface.

75 By observation of Fig. 7 a clear understanding of the method of performing the roughening operation may be had. The shoe is held in

the operator's two hands, kept with an upward pressure against the gauge point at $12c$ while drawing it across the legs $12b$.

It is, of course, obvious that should the positions of the parts be reversed, that is, the guard with the gauge mounted thereon exactly as seen in Fig. 7, but turned upside down, and the direction of rotation of the wire brush wheel reversed from that shown in Figs. 8 and 9, the result, insofar as the roughening process is concerned, would be carried out and accomplished in the same manner as with the parts arranged as shown. However, the method illustratively disclosed seems preferable for the reason that the workman can better observe the work as it is being done.

It is possible to construct the guard member 5 of an arcuate shape in side view, as shown in Fig. 15.

In this instance the portion of the wire brush 20 wheel which projects beyond the legs $12b$, describes, in side elevation, a somewhat flattened crescent shape, and the wheel, in operation, is not so liable to "grab" the overlapping portions of the leather upper and pull the shoe out of 25 the workman's hands than would be the case were the guard member made straight and not equipped with a gauge 12 .

While for convenience of description, the roughing tool has herein been described and illustrated as a wire brush wheel, it is to be understood that the invention is not limited to the use of such a wheel and that provision of any suitable or desired form of roughing wheel is contemplated, whether or not it be of the 35 wire brush type.

A roughing machine with my improvement incorporated therein enables a workman to scarify the overlapping portions of a greater number of shoes than he is capable of doing when using 40 conventional methods, in a day's work.

Losses, sometimes quite considerable, suffered by the manufacture through negligence of the workman, or due to the physical impossibility of always holding the shoe against the wheel in 45 the correct and exact position to prevent roughing the surface too far up the sides of the shoe, is practically eliminated by the use of my gauge device. And, although this defect in the shoe 50 may not appear when the shoe is new, after being worn and stretched it cannot be concealed, thus the demand of the customer to have it replaced by a perfect one is generally forthcoming.

55 By reason of the fact that with my gauge a tangible means is provided for guiding the shoe during the roughing operation, a workman is relieved of the strain and is required to give less strict attention to keeping the shoe within bounds than obtains with most other methods of doing this work.

What I claim is:

1. An upper roughing machine comprising a rotatable roughing wheel, a casing for said wheel 65 having an open front, a guard covering such open portion of said casing and having a guide groove in its forward face, said guard having an opening located in said groove through which part of the periphery of said wheel extends, and a gauge having an outwardly extending shoulder for engaging the side of a lasted upper and a pair of straight spaced arms extending forwardly beyond said shoulder for engaging entirely across the bottom of a lasted upper, said gauge being 70 75

fastened in said guide groove with its arms located at either side of said opening.

2. An upper roughing machine comprising a rotatable roughing wheel, a casing for said wheel, a guard covering the front portion of said casing, said guard having an opening therein through which part of the periphery of said wheel extends, a gauge having an outwardly extending shoulder for engaging the side of a lasted upper and a pair of straight spaced arms extending forwardly beyond said shoulder for engaging entirely across the bottom of a lasted upper, said gauge being normally fixed to said guard with its arms located at either side of said opening.

3. An upper roughing machine comprising a rotatable roughing wheel, a guard plate located in front of said wheel and having a guide groove in its forward face, there being an opening in said groove through which a peripheral portion of said wheel extends, and a gauge in said groove, said gauge having a forwardly project-

ing shoulder overhanging one end of said opening and a pair of spaced arms extending forwardly of said shoulder, said arms being fitted in said groove at either side of said opening and being shaped so as to extend outwardly beyond the front face of said guard plate a distance at least sufficient to permit reception of the fingers of an operator between the front face of the guard plate and the plane of the top edges of said arms.

4. In an upper roughing machine, a gauge member comprising a body portion having an outwardly projecting shoulder for engaging the side of a lasted upper and having straight spaced arms extending forwardly of said shoulder for engaging the bottom of a lasted upper, said arms being provided with elongate anti-friction rollers, engageable entirely across the bottom of said upper, and a roughing wheel having its roughing periphery extending between and slightly beyond said spaced arms.

ARTHUR T. TEMPESTA.
